APPARATUS FOR DEMONSTRATING
FIGURE-MOLDING GARMENTSFrank Willis Moore, Letchworth, England, as-
signor to The Spirella Company Inc., Niagara
Falls, N. Y., a corporation of New YorkApplication August 31, 1932, Serial No. 631,131
In Great Britain November 27, 1931

7 Claims. (Cl. 35—12)

This invention relates to apparatus for demonstrating the fit and effect on the figure of figure-molding garments.

In demonstrating corsets and other figure-molding garments the practice heretofore has been to apply the garment to the individual so that its fit and figure-controlling effect may be viewed in a mirror. This mode of demonstrating such garments is not entirely satisfactory, inasmuch as it does not and cannot provide any exact and detailed comparison between the figure in various conditions of corseting, for example, in the uncorseted condition and as modified by one or more different figure-molding garments. The same situation has been present in demonstration by models, where only the result obtained by the corset worn at the moment can be observed. In the demonstration of certain types of garment, such as the so-called figure-training garments, it would be particularly helpful if accurate and detailed comparison of the figure in various corseted conditions and garments could be made, but no satisfactory means to that end has been available.

It is among the objects of this invention to provide apparatus for effectively demonstrating and permitting detailed visual comparison of the results upon individual figures of different figure-molding garments, whereby an individual may be fitted with one or more such garments and the results obtained examined and compared at leisure, both with respect to one another and the uncorseted condition, which is easily used, of simple and relatively inexpensive construction, and is adapted for both individual and group demonstrations. Other objects will appear to those skilled in the art from the following description of the invention.

In accordance with the invention there is projected upon a translucent screen a silhouette of the figure of an individual in one condition of corseting, the outline of the silhouette thus produced is traced upon the screen, and the silhouette of the figure in another condition of corseting is then projected upon the screen in superimposed position relative to the first tracing, and its outline is then, preferably, also traced upon the screen. The superimposed silhouettes thus obtained permit satisfactory minute and accurate comparison of the figure in various conditions of corseting, for example comparison between the uncorseted and corseted conditions, or between the results obtained with different figure-molding garments.

As used herein, the term "figure-molding gar-

ments" is applied generically to designate garments used to modify and control the human figure, for example, corsets, corselettes, brassières, and the like, and for brevity of reference the terms "corset", "corseted condition", and the like will be used to designate all such garments and the result produced thereby.

The apparatus provided by the invention comprises a translucent screen upon which silhouettes of the human figure may be projected and traced, a source of light adapted for the projection of the silhouettes, and means positioned between the light source and the screen for positioning an individual successively in the same position for production of comparatively superimposed silhouettes. Preferably, the apparatus comprises a framework provided with means for replaceably holding a translucent material, such as paper, so that the screen with its silhouette tracings may be removed, if desired, as for future reference. In this manner new screens may be inserted for each demonstration, and at a very little cost.

Various means may be used for permitting an individual to successively resume and retain the same position in successively different corseted conditions for production of the desired superimposed silhouettes. Most suitably this comprises means for positioning the feet, legs and head, as will be described more fully herein-after.

The invention may be described further in connection with the accompanying drawings, in which Figure 1 is a front perspective view of an apparatus embodying the invention, the translucent screens being removed for purposes of illustration; Fig. 2 a perspective view from the rear of the apparatus, showing the screens in place with various silhouettes traced thereon; Fig. 3 a top plan view of the base of the apparatus shown in Figs. 1 and 2; Fig. 4 a side elevation of the base; Fig. 5 a plan view of the base in folded position; Fig. 6 a top plan view of the apparatus shown in Fig. 1; Fig. 7 a fragmentary side view of the upper portion of the apparatus shown in Figs. 1 and 2 on a somewhat larger scale, showing the head-rest; Figs. 8 and 9 views showing one form of screen clamp; Figs. 10 to 13 views, partly in section, showing framework elements; and Fig. 14 an enlarged perspective view of the lamp-projection stand shown in Fig. 2.

Having reference now to the drawings, the embodiment shown comprises a base-board 1 having a flat top 2 connected to spaced battens 3, and preferably formed of two parts connected along 110

a center line 4 by hinges 5 so that the base-board may be folded for packing or transportation. At each corner and at the center of the front edge of base-board 1 there are mounted vertical posts 6 supported in apertured lugs 7, Fig. 3, connected to the base-board. For facility in assembling the framework, posts 6 are of detachable construction, those shown being formed in three parts. Each comprises an intermediate length 8, Fig. 10, 10 and two end members 8a, Fig. 11. The ends of member 8 have screw-sockets 9 adapted to receive a threaded pin 10 fixedly carried at one end of end members 8a. The opposite ends of members 8a are provided with pins 12 which, in 15 the lower member, engage the aperture in lug 7, and in the upper member is adapted to receive a ball 13 for purposes of ornamental appearance.

Angle irons 14 and 14a of greater length than the front of base 1 are connected to front posts 20 6, for example by providing spaced apertures through which pins 12 of members 8a pass prior to receiving balls 13, as shown in Fig. 7. These angle irons contribute to the finished appearance of the apparatus and brace the posts at the front 25 of the apparatus.

The rear posts are spaced by a tubular brace 15, and the front and rear posts are spaced by tubular braces 16, 17, 18 and 19, Fig. 1, all mounted by passing apertures in their extremities over screws 30 12 at the upper ends of the posts before attaching balls 13. Preferably tubes 15, 17 and 18 are connected together, as by welding, to form a fixed triangular bracing member, for additional rigidity and to facilitate assembly and disassembly 35 of the apparatus.

The outer ends of angle irons 14 and 14a are connected by additional vertical posts 6a, similar 40 in construction to posts 6. The framework is braced against side-sway by diagonal bracing rods inserted in the framework. Advantageously these comprise tubular members 20 and 21, Figs. 12 and 13. One of the rods, for example 21, is provided at one end with a pin 22 having one end 45 freely movable in the rod, the outer end of the pin being provided with screw-threads 23 upon which a nut 24 is rotatably mounted to form a shoulder abutting the end of rod 21 to limit inward movement of pin 22 therein. The outer end of pin 22 enters one end of rod 20 and seats 50 against a fixed stop 25. The opposite ends of tubes 20 and 21 are provided with forks 27 which engage posts 6, as shown in Fig. 1. By manipulating nut 24, the length of the bracing members 55 can be adjusted for rigid bracing of the framework.

A screen upon which silhouettes of an individual standing upon the base may be projected is carried by the framework at the front of base 1. This screen may be formed of any material for 60 projection and tracing of the silhouette. Advantageously it is formed from paper removably held in clamps carried by the top and bottom of the framework. Although a single screen may be used, it is preferred to use two screens supported 65 in side-by-side relation in the panels formed by front posts 6, for purposes hereinafter described.

One form of clamp which may be used to replaceably support the screens is shown in Figs. 8 and 9. A backing member 27 and a cover 70 member 28, suitably of wood, are connected along their upper edges by hinges 29. Backing member 27 is provided with a longitudinal groove 30 adapted to receive a corresponding fillet formed on cover 28, and the backing member is also provided with a groove 31 for reception of a bowed

leaf-spring 32 anchored at one end to the backing member. This spring forces cover 28 outwardly when the clamp is opened. Bolts 33 project forwardly through the backing member and slots formed in cover member 28, and are engaged by wing nuts 34. One such clamp is suspended in each of the front panels by means of hooks 35 which engage angle iron 14a. Similar clamps are connected to the bottom of the panels, for example by cords, not shown, connected to the clamps and drawn under angle iron 14 and thence to hooks 40, Fig. 6.

In the use of the clamps just described, a strip of paper, or other suitable material, of appropriate width and length is inserted in the clamp shown in Figs. 8 and 9 between the front and back members. Wing nuts 34 are then tightened to close the clamp and grip the paper between groove 30 and its co-operating fillet. The screens are thus held sufficiently tightly and may be replaced quickly and easily by new screens.

Curtains may be hung in front of the screens from a rod 36 connected to angle iron 14a by brackets 37. Additional end, or wing, curtains may be provided at the extreme sides of the apparatus, as shown in Figs. 1 and 2, by hanging them on rods 38, pivotally carried by side rods 6a.

Mounted rearwardly of the base is a source of light suitable for projecting upon the screen the silhouette of a person positioned upon the base-board. Such light source may take any of a variety of forms, that shown comprising a lamp-stand 41 adapted to receive a projection lamp 42 which may be moved from side to side on its support for directly projecting silhouettes 100 upon either of the screens. In the practice of the invention lamp 42 is moved on the stand so that a shadow of the rear post 6 behind the screen to be used is cast in the center of that screen.

An important feature of the apparatus is the 115 provision of means for permitting an individual to successively resume the same position relative to the screen, and to retain such position, so that successive silhouettes may be substantially superimposed for minute visual comparison. The 120 means shown comprises blocks 43 connected to the base and provided with laterally projecting foot stops 44. Projecting upwardly from blocks 43 are supports 45 which carry at their upper 125 ends laterally projecting cross members 47. The positions of these members are such that a person may stand on the base-board with the toes in contact with projections 44 and the legs just below the knees in contact with the arms of member 47, which latter are preferably padded 130 to avoid discomfort to the individual while retaining position thereagainst.

It is preferred also to use additional means for obtaining substantially identical superimposition and for ease in retaining the position during tracing of the silhouette. To this end the apparatus is provided with adjustable head rests, the form shown comprising a curved arm 48 pivotally connected by a bolt 49 to cross-bar 17, or 19, as the case may be, and a rod 50 pivotally connected by a bolt 51 to cross rail 16, or 18, as the case may be. At its lower end, rod 50 passes through an apertured stud 52 carried on the free end of curved arm 48, and a clamping screw 53 in stud 52 permits rods 48 and 50 145 to be clamped in desired relative position. At the lower end of rod 50 is a curved padded headrest 54 whose position may be adjusted by means of a set screw 55.

In order further to assist the individual, or 150

model, to remain stationary rear posts 6 are positioned so that the individual being silhouetted may extend her arm horizontally and grasp the adjacent rear post by the hand.

5 In order to facilitate shipment and assembly of the apparatus, cross members 47 are hingedly connected to uprights 45, which in turn are hinged, as seen in Fig. 1. Thus the entire base may be folded substantially flat, as shown in 10 Fig. 5.

In the use of the apparatus provided by this invention, an individual is positioned between the screen and the light with the toes and knees positioned against foot-stops 44 and knee braces 15 47, and with the head suitably positioned in rest 54. That is, in the use of the apparatus shown in the drawings the individual stands facing toward the left of Fig. 1 so that her left arm is adjacent the screen and her right arm is toward 20 the rear posts 6 and light source 42. The silhouette cast upon the screen is then traced in outline upon the front of the screen, as by a brush and paint. During this operation the individual extends the right arm straight out from 25 the body and grasps the adjacent rear post, for ease in retaining position without undue movement. The left arm, adjacent the screen, is kept close to the side. Assuming that the silhouette of the individual has been projected and traced 30 upon the screen with the individual in an uncorseted condition, there is then applied a garment whose effect upon the figure is to be demonstrated. The silhouette of the figure as thus modified is then projected in comparatively superimposed position, and its outline is traced. The foot, knee and head rests, and gripping of 35 the appropriate rear post 6 ensure that the previous position is resumed with substantial exactitude. This then permits observation of the effect 40 of the garment upon the uncorseted figure. The individual referred to may be a prospective garment purchaser, or a model demonstrating before an audience, as will be understood in the art.

45 The invention is particularly useful in demonstrating the so-called figure-training garments, i.e. garments of the made-to-measure type which are designed upon anatomical principles and which are intended to provide anatomically correct support. The design of these garments, and their effect upon the human figure, are markedly different from those of the ordinary ready-made type. For example, in figure-training garments, each garment is made from measurements of the 50 particular individual, and it is designed to provide support for the muscles and internal organs in an upward and backward direction from the pelvic region as a base, and thus to conform to the natural functioning of normal healthy muscles 55 in co-operation with the bony framework. This action is in direct contrast to ordinary ready-made garments, which usually tend to produce a downward and forward compression, which are designed and cut for average figures, and which 60 seldom fit properly. Figure-training garments are conducive to health, maximum comfort, and satisfactory figure-molding. Their benefits, as contrasted with ordinary ready-made garments, and the foundation for outer garments which is 65 thus provided, may be admirably demonstrated by means of this invention.

To this end, and assuming that a model is demonstrating to an audience, the model wearing an ordinary corset is positioned, for example, in front of screen A, and the silhouette is

projected and outlined upon the front of the screen. The model in an uncorseted condition then takes up a position in front of screen B and the silhouette is projected and traced thereon. This provides for comparison between the uncorseted and ordinarily corseted conditions.

80 The model is now fitted with a fitting garment adapted for use in taking accurate measurements from which to make figure-training garments and, as thus corseted, the silhouette is projected 85 comparatively to that of the uncorseted position upon screen B. This permits a comparison between the uncorseted condition and the result obtained from correct corseting, as exemplified by the fitting garment. Finally the model assumes a garment made from measurements taken with the fitting garment, and the silhouette in 90 this condition is projected comparatively to that initially traced upon screen A (in the ordinary corseted condition). This then permits a comparison with the effect of an ordinary corset 95 and one designed and tailored upon figure-training principles.

95 In this manner, the improvement in figure and other details obtained by the use of figure-training garments, as well as the efficacy of fitting through the medium of the fitting garment may be observed in a manner which has not been possible heretofore. Because the silhouettes are superimposed, detailed and accurate observation 100 is possible, and since the outlines of the silhouettes are reduced to permanent form, it is possible to examine them at length. Most suitably, the various silhouettes are traced in different colors for ease of comparison. It will be understood, of course, that the relative superimposition of the silhouettes in the various corseted 105 conditions may be varied from the example just given.

110 If desired, the side, or wing, curtains held by rods 38 may be replaced by angularly arranged mirrors, to enable observers from the front of the screen to view the operations taking place behind the screen. Blocks 48 are preferably positioned close to the screens but at a distance 115 therefrom such that corsets or other garments may be placed upon the individual and correctly adjusted while the latter remains in position. Likewise, other means than those described may be used for permitting the individual, or model, 120 to resume and maintain the necessary positions. If desired, the base and framework may be mounted rotatably, i.e. as a turn-table, so that the operations of adjusting the garments upon 125 the model can be carried on in full view of an 130 audience instead of behind the screen.

135 According to the provisions of the patent statutes, I have explained the principle, construction and mode of use of my invention, and have described what I now consider to be its best embodiment. However, I desire to have it understood that, within the scope of the appended claims, the invention may be practiced otherwise than as specifically illustrated and described.

I claim:

140 1. In an apparatus for positioning a person before a screen, the combination of a vertically disposed translucent screen for projection and tracing thereupon the silhouette of a human figure, a source of light behind the screen for 145 projecting upon the screen the silhouette of a person positioned between the light and the screen, and means disposed in fixed position between the light and the screen to compel the person using said means successively to resume 150

substantially the same positions for production of superimposed silhouettes for purposes of comparison.

2. In an apparatus for positioning a person before a screen, the combination of a vertically disposed translucent screen upon which silhouettes of a person are projected and traced for detailed visual comparison, and means including spaced foot-stops disposed in fixed position before and adjacent said screen to compel a person using said means successively to resume substantially the same position for production of comparatively superimposed silhouettes illustrative of changes in figure and posture of the person, such as changes produced by figure-molding garments.

3. In an apparatus for positioning a person before a screen, the combination of a vertically disposed translucent screen upon which silhouettes of a person may be projecting and traced for detailed visual comparison, spaced foot-stops and leg braces held in fixed position adjacent and behind said screen, and an adjustable headrest cooperating with said stops and braces to compel a person using said foot-stops, leg braces and headrest successively to resume substantially the same position for production of comparatively superimposed silhouettes illustrative of changes in the figure and posture of the person, such as changes produced by figure-molding garments.

4. In an apparatus for positioning a person before a screen, the combination of a framework, a vertically disposed translucent screen connected to the front of said framework for projection and tracing thereon of silhouettes of the human figure, an adjustable headrest connected to said framework behind said screen, and spaced foot-stops and leg braces disposed in fixed position behind the screen, said headrest, stops and braces cooperating to compel a person using them successively to resume substantially identical positions for production of comparatively superimposed silhouettes illustrative of changes in the figure and posture of the person, such as changes produced by figure-molding garments.

5. In an apparatus for positioning a person before a screen, the combination of a base, a framework connected to the base, a translucent screen replaceably connected to the framework

at the front of said base for projection and tracing thereon of silhouettes of the human figure, a source of light positioned rearwardly of said base, foot-stop and leg brace members connected to said base rearwardly of the screen, a headrest connected to said framework, and a hand-rail connected to said framework for gripping by a person being silhouetted and positioned between said stops and light source in the path of the light therefrom, said headrest, stops, braces and rail cooperating to compel a person using them successively to resume substantially identical positions for production of comparatively superimposed silhouettes illustrative of changes in the figure and posture of the person, such as changes produced by figure-molding garments.

6. In an apparatus for positioning a person before a screen, the combination of a framework, a pair of spaced clamps connected to the framework, a sheet of translucent material, such as paper, gripped in said clamps and forming a screen for receiving a projected shadow of a person's figure and upon which to trace the silhouette thereof, a source of light positioned rearwardly of said screen, and means between said light source and screen to compel a person using said means successively to resume substantially the same position for production of comparatively superimposed silhouettes illustrative of changes in the figure and posture of the person, such as changes produced by figure-molding garments.

7. In an apparatus for positioning a person before a screen, the combination of a framework, a plurality of translucent screens carried by said framework in side-by-side relation for receiving projected shadows of a person's figure and upon which to trace the silhouette of said shadows, a source of light positioned rearwardly of said screen, and means disposed in fixed position between said light source and screen and connected to said framework to compel a person using said means successively to resume substantially the same position for production of comparatively superimposed silhouettes, said screens cooperating to provide detailed and accurate comparison of changes in the figure and posture of the person, such as changes produced by figure-molding garments.
